UNITED STATES PATENT OFFICE.

GEORGE E. TINKER, OF NEW YORK, N. Y.

CONDUCTOR.

SPECIFICATION forming part of Letters Patent No. 730,058, dated June 2, 1903.

Application filed January 9, 1903. Serial No. 138,401. (No model.)

To all whom it may concern:

Be it known that I, GEORGE E. TINKER, a citizen of the United States, and a resident of the city of New York, borough of Brooklyn, in the county of Kings and State of New York, have invented a new and Improved Conductor, of which the following is a full, clear, and exact description.

This invention relates to an improvement in conductors adapted especially for what is commonly called the "third-rail" system of electric railways.

The invention comprises a conduit formed of a number of transversely-disposed brackets 15 of essentially C shape, having each at one of its vertical sides an opening therein, these brackets being provided with downwardly-extending lugs, spaced from each other and adapted to engage a non-conducting support. 20 Around the brackets is arranged a non-conducting sheathing, forming a complete tube, such sheathing having an opening therein conforming to the openings in the brackets, so that the shoe and its arm may be projected 25 through these openings and engaged with a conductor-rail fastened to the brackets.

This specification is a specific description of one form of the invention, while the claims define the actual scope thereof.

Reference is to be had to the accompanying drawings, forming a part of this specification, in which similar characters of reference indicate corresponding parts in both views.

Figure 1 is a cross-section of the invention, 35 and Fig. 2 is a longitudinal section of the invention.

a indicates the railway-rails, and b the cross-ties thereof.

c indicates a number of metallic brackets, 40 which are preferably formed of cast-iron and are arranged along the road at certain set distances apart. These brackets c are inclosed by an asbestos covering d, and over this covering d is arranged a wooden sheathing e, the parts d and e being continuous to form a tube, which is split longitudinally near its lower inner side, as indicated at d', this split 45 occurring opposite the space c' between the arms of the brackets c. The whole structure 50 c, d, and e is mounted alongside of the track in the usual position, and according to the construction here shown this mounting is ef-

fected by means of pairs of lugs c², which depend from the bottom of the brackets c and are fastened to insulating-chairs f, mounted 55 on the cross-ties b or any other suitable support. These lugs c² extend down through the asbestos covering d and wood sheathing e, and the chairs f project upward between the lugs. This securely mounts the conductor 60 and its protecting coverings in place. As shown in Fig. 1, the conductor or contact rail g is suitably mounted within the brackets c and runs through the before-said split tube. On this rail is adapted to run the shoe 65 h of the car, this shoe being carried by an arm i, which is projected through the slits c' d' in the tube d e into the interior thereof and supported from the car in the usual or any preferred manner. From this construction it will be apparent that the contact may be effectually made at all times irrespective 70 of the conditions of the weather and that no ice, snow, or other foreign matter may enter into the tube d e and clog the contact-rail g. 75 This tube being made of non-conducting material the current is transmitted solely through the contact-rail g.

Various changes in the form, proportions, and minor details of the invention may be resorted to at will without departing from the essential principles thereof. Hence I consider myself entitled to all such variations of the invention as may lie within the scope of my claims.

Having thus described my invention, I claim as new and desire to secure by Letters Patent—

1. A conductor, comprising the combination with a support, of a number of transversely-disposed brackets, each of said brackets having an opening in one of its vertical walls, said openings being in alignment with each other and the brackets also having downwardly-extended lugs adapted to be fastened 90 to the support, a conductor passing through the brackets and mounted thereon, and a non-conducting sheathing inclosing the brackets and forming a complete tube, said tube being split longitudinally in registry 95 with the openings in the sides of the brackets, for the purpose specified.

2. A conductor, comprising the combination with a support, of a number of trans-

versely-disposed brackets, each of said brackets having an opening in one of its vertical walls, said openings being in alinement with each other and the brackets also having downwardly-extended lugs adapted to be fastened to the support, a conductor passing through the brackets and mounted thereon, and a non-conducting sheathing inclosing the brackets and forming a complete tube, said tube being split longitudinally in registry with the openings in the sides of the brackets,

for the purpose specified, and the said insulating-tube extending completely under the brackets and having the lugs thereof projected through it.

In testimony whereof I have signed my name to this specification in the presence of two subscribing witnesses.

GEORGE E. TINKER.
